UNITED STATES PATENT OFFICE

ABRAHAM HOLTZ, OF BRONX, NEW YORK

DESIGN FOR A FRINGE

Application filed August 29, 1929. Serial No. 32,619. Term of patent 3½ years.

To all whom it may concern:

Be it known that I, ABRAHAM HOLTZ, a citizen of the United States, residing in the Bronx, county of Bronx, State of New York, whose post-office address is 16-18 West 22nd Street, city, county, and State of New York, have invented a new, original, and ornamental Design for a Fringe, of which the following is a specification, reference being had to the accompanying drawing, forming part thereof.

The figure is a plan view of a fringe showing my new design.

The drawing shows a repeat design and the dot and dash lines include one complete element.

I claim:

The ornamental design for a fringe substantially as shown and described.

ABRAHAM HOLTZ.
